UNITED STATES PATENT OFFICE

1,929,463

RAZOR BLADE STROPPER

Frank E. Wolcott, West Hartford, Conn., assignor to The Beardsley & Wolcott Mfg. Co., a corporation of Connecticut

Application April 17, 1928. Serial No. 270,662

12 Claims. (Cl. 51—80)

My invention relates to razor blade stroppers.

It has for its object to provide an improved stropper of the general type described and claimed in my Patent No. 1,550,861, patented August 25, 5 1925, wherein it is made possible for the user to adjust the rolls in an improved manner, over a wider range and with greater facility in order to vary the pressure on the blade or to take up wear. A further object of my invention is to 10 provide an improved pin and cover construction for such a stropper whereby all necessity for providing shims for the blade positioning members or for changing of these shims by the user or between adjustments, is eliminated, and whereby 15 a wider and generally more satisfactory and expeditious adjustment is obtainable by merely varying the pressure exerted by the hand holding the stropper during the sharpening operation. These and other objects and advantages of my 20 improved construction will, however, hereinafter more fully appear.

In the accompanying drawing I have shown, for purposes of illustration, one embodiment which my invention may assume in practice.

25 In this drawing,—

Figure 1 is an end elevation of a stropper equipped with my improvement, the same being shown open with a blade in position therein;

Fig. 2 is a transverse sectional view showing 30 the stropper closed, the maximum depressed position of the parts also being shown in dotted lines, and

Fig. 3 is a longitudinal sectional view on line 3—3 of Fig. 2.

35 In this illustrative embodiment I have shown a stropper of the general construction of my patent mentioned, and including a frame 1 having pivoted covers 2 thereon and spaced rolls 3 carried by the frame and cooperating movable rolls 4 carried by the covers, these rolls being operatively connected by means of spur gearing, generally indicated at 5 and carried by the frame 1 and driven from a handle 6, and adapted when the covers are closed to sharpen a blade 7 suitably 45 positioned on the spaced blade positioning members 8 of improved construction, hereinafter described.

Referring more particularly to these members 8, it will be noted that, as distinguished from 50 the use of rigid stationary members 8 underlying the adjacent edges of the covers 2 and cooperating removable shims upon the base thereof, I have provided members 8 of a depressible type. In a preferred construction, these members 8 are normally held in a projected position slightly elevat-

ing the covers 2, by springs, herein in the form of coiled springs 9 and seated in bores 10 in tubular receiving members 11 carried on the bottom of the frame 1. Herein, these members 11 are connected to the frame 1 by upwardly extending 60 screws 12 received in apertures 13 in the bottom of the frame and threaded into larger bores 14 in the lower ends of the members 11. Moreover, it will be noted that each of the members 8 is provided with a projection, herein in the form of 65 a flange 15, on its lower end adapted to move in the bore 10 when the body of the members 8 moves in a smaller upper bore 16, the flanges 15 also acting to limit the longitudinal movement of the member 8.

70 In the use of my improved construction, it will be noted that when a blade is placed in the position shown in Fig. 1 the blade is supported only at its edges and directly on the upper surfaces of the rolls 3. When the covers 2 are moved 75 down into their initial closed position shown in full lines in Fig. 2, the rolls 4 are brought into engagement with the rolls 3 so that sharpening may be effected upon rotation of the handle 6. If further pressure is desired, depression of the 80 covers 2 will obviously result in a depression of the members 8, the coiled springs 9 then yielding and enabling the covers 2 to be further depressed to increase the pressure. Obviously, the pressure will also be limited by contact of the adjacent edges of the covers 2 with one another. 85 Further, when the fingers applying the pressure are released, the covers 2 will be moved back by the springs 9 to their initial position shown in Fig. 2. In case the rolls are worn, it will be evident that the same operation will result in bringing the rolls 3 and 4 closer together in such 90 manner as to compensate for this wear.

95 As a result of my improvement, it is made possible to obtain any desired pressure. It is also possible to permit the user to vary the pressure as he desires. Thus, a user can at will obtain the pressure effects obtainable by a barber. Moreover, he can do this conveniently, by simply varying his grip on the stropper. All necessity for 100 providing the different shims described in my patent mentioned is eliminated, and further, it is made possible to eliminate any necessity for the removal of these shims by the user, the stropper instead being furnished from the factory 105 in such form that by simply varying the pressure which he applies to the covers 2 the user can adapt the stropper to any desired pressure or compensate for wear in such manner as may be necessary. It will also be evident that although 110

a wide range of adjustment is permitted before further depression is prevented, through the co-operation of the depressible members 8 and the engaging or abutting edges of the covers, means are provided which prevent the user from applying too great pressure. The springs 9, by their opposition to the pressure exerted by the operator, also tend to prevent too great unintentional pressure which may be unnecessary and of course return the covers to initial position as soon as pressure is removed. Attention is also directed to the fact that the new construction is adapted to be embodied in stroppers of my prior construction with a minimum of expense. It will also be noted that the particular construction illustrated is adapted to long use in service. These and other advantages of my invention will, however, be obvious to those skilled in the art.

While I have in this application specifically described one embodiment which my invention may assume in practice, it will be understood that the same is shown for purposes of illustration only, and that the invention is not limited thereto but may be modified and embodied in various other forms without departing from its spirit or the scope of the appended claims.

What I claim as new and desire to secure by Letters Patent is:—

1. In a stropper, cooperating rolls including movable rolls, the latter carried on pivoted cover members, depressible spring supported slidable blade positioning pins between said first mentioned rolls normally holding said covers slightly elevated and depressible upon pressure of said covers to increase the pressure of the movable rolls thereon against their cooperating rolls, and means on said cover members limiting the possible depression thereof.
2. In a stropper, cooperating rolls including movable rolls, the latter carried on pivoted cover members, depressible spring supported slidable blade positioning pins between said first mentioned rolls normally holding said covers slightly elevated and depressible upon pressure of said covers to increase the pressure of the movable rolls thereon against their cooperating rolls, and means on said cover members limiting the possible depression thereof, said means including adjacent edges adapted to engage upon depression of said covers and depressible members.
3. In a stropper, a frame carrying spaced rolls, separately pivoted cover members on said frame each carrying a cooperating roll operatively connected to said first mentioned rolls, blade positioning means, and a plurality of upstanding spring-pressed slidable plungers between said spaced rolls and depressible by said cover members to permit an increase in pressure of said cooperating rolls.
4. In a stropper, a frame carrying spaced rolls, separately pivoted cover members on said frame each carrying a cooperating roll operatively connected to said first mentioned rolls, and a plurality of upstanding slidable means carried by said frame each having a portion extending through a blade being sharpened and a spring portion providing a resilient support for a cover member.
5. In combination, a frame having laterally

spaced lower rolls therein, separately pivoted cover members on said frame separable along a face between said pivots, cooperating upper rolls on said members operatively connected to said first mentioned rolls, and a plurality of spring supported and upstanding slidable members each engageable with the adjacent edges of both cover members.

6. In a stropper, means to hold a double-edged blade in stropping position, means for simultaneously stropping both sides of both edges of said blade, and spring-pressed slidable means passing through said blade for holding said stropping means apart, the pressure on the edges of said blade being controlled by pressing said stropping means together.

7. In a stropper, a fixed stropper roll, a co-operating movable stropper roll, means for holding a blade in stropping position, and slidable spring-pressed means passing through said blade for normally holding said rolls apart, the pressure between said rolls being adapted to be increased when said rolls are pressed together.

8. In a stropper, a pair of relatively movable stropper rolls, slidable spring-pressed means for holding a blade in stropping position between said rolls, said means passing through said blade and being yieldable in a direction perpendicular to the blade and serving to control and limit the pressure between said rolls.

9. In a stropper, a frame carrying a roll-holding member, a cooperating roll-holding cover member pivoted to said frame, and slidable spring-pressed blade-positioning means carried by said frame and passing through the blade to permit the pressure between said rolls to be manually varied, and means to limit said pressure.

10. In a stropper, a frame carrying a pair of spaced stropper rolls, a pair of roll-holding cover members pivoted to said frame, yieldable spring-pressed slidable blade-positioning means on said frame between said spaced rolls, passing through the blade, and engageable with both of said cover members, whereby manual pressure exerted upon said cover members will vary the stropping pressure between said rolls, the pressure between said rolls being limited by the engagement of adjacent inner edges of said cover members.

11. In a stropper, a frame carrying a pair of spaced stropper rolls, a pair of roll-holding cover members pivoted on said frame, a pair of upwardly spring-pressed downwardly slidable pins carried on said frame and engageable by the adjacent inner edges of said cover members, the pressure between said stropping rolls being controlled by the pressure exerted upon said cover members and limited in maximum amount by the engagement of the adjacent inner edges thereof.

12. In a blade stropper, a frame carrying a roll-holding member, and a cooperating spring-pressed cover member pivoted to said frame, said cover member being normally held at a relatively elevated position by slidable spring means passing through the blade and adapted to be manually depressed to increase the pressure of said rolls upon the blade.

FRANK E. WOLCOTT.
